SCISSORS CONSTRUCTION

Ernst L. Zepf, Tuttlingen, Wurttemberg, Germany, assignor of fifty percent to August Klenk, Maspeth, N.Y.

Filed Dec. 6, 1961, Ser. No. 157,536

8 Claims. (Cl. 30—266)

This invention relates in general to scissors and shears constructions, and in particular to a new and useful scissors or shears having means for adjusting the cutting action thereof.

Prior to the present invention, it has been known to provide means for adjusting the cutting action of co-operating scissors blades such as by providing a threadable bolt member at the location of the pivot for such blades to vary the tension acting to hold the blades together. A disadvantage in such constructions is that after a few movements of operation of the blades for the purpose of cutting, the bolt tensioning members loosen and the co-operable action of the blades must be readjusted. Where additional means are provided to lock the threaded bolt elements in the adjusted position, such means have the disadvantage that they tend to become wedged in a locked position, become misaligned from the associated bolt members, and tend to wear rapidly.

In accordance with the present invention, there is provided an improved scissors construction which includes a first blade having a bore or an opening therethrough at its pivot location with an upstanding collar member formed around the bore and projecting into a slightly larger bore of the other scissors element. The other scissors element may pivot easily about the collar member. The collar bore aligns with the bore of the first scissors blade element to permit insertion of a tensioning bolt element or lever member which is threaded on one side to receive an adjusting nut and carries a lever arm portion on its opposite end which extends outwardly and includes a widened tip portion or nose which is adapted to press downwardly against the adjacent blade element. The nose forms a fulcrum point to permit tension to be applied at such location through the lever arm portion. The cutting action for the scissors may be easily adjusted by rotating the adjusting nut to vary the tension acting to hold the blades together by causing the nose on the end of the lever arm to press downwardly against the adjacent blade.

A feature of the construction is that the collar or sleeve member which is located adjacent the lever portion of the tensioning bolt provides a shoulder which aligns the lever portion along the axis of the remotely underlying blade or the blade to which the collar member is affixed. Thus, when the scissors blades are pivoted during cutting action, the lever member through the nose is made to bear against the adjacent blade and is held thereagainst in a stationary position by the sleeve member so that it may not be moved by the pivotal movement of the adjacent scissors blade. With the inventive construction, it is possible to use the single tensioning bolt member with an adjusting screw for adjusting the tension between scissors blades and the cutting action thereof.

Accordingly, it is an object of this invention to provide an improved scissors construction.

A further object of the invention is to provide a scissors including cooperating blade elements which are pivotal about a bolt member which includes a projecting lever arm portion adapted to overlie and bear against one of the blade elements and further including an adjustable nut overlying the opposite blade element and threadable on the bolt member for adjusting the tensioning between the scissors blades.

A further object of the invention is to provide a scissors blade construction which includes a first blade having a

2

pivot bore defined therethrough, a second blade having a sleeve element extending therethrough and defining a second pivot blade bore in alignment with said first blade pivot bore, and further including a bolt element having one portion adjacent the collar member extending outwardly from the bore at a spaced location from the face of the blade and having a portion bearing downwardly at its outer end against the associated blade, the collar member holding the bolt member against rotation, and including an adjusting nut threadable on the opposite side of the bolt member for varying the tension at which the projecting point bears against the associated blade and hence the tension between the blades.

A further object of the invention is to provide a scissors construction which is simple in design, rugged in construction and economical to manufacture.

The various features of novelty which characterize the invention are pointed out with particularity in the claims annexed to and forming a part of this specification. For a better understanding of the invention, its operating advantages and specific objects attained by its use, reference should be had to the accompanying drawings and descriptive matter in which there is illustrated and described a preferred embodiment of the invention.

25 In the drawings:

FIG. 1 is a fragmentary side elevation of a scissors having means for adjusting the cutting action of the blades, constructed in accordance with the invention;

FIG. 2 is a somewhat enlarged fragmentary elevation and partial section of the scissors indicated in FIG. 1;

FIG. 3 is a plan view of the scissors indicated in FIG. 1 with the blades opened;

FIG. 4 is an elevational view of the tensioning bolt member;

35 FIG. 5 is an elevational view of the adapting nut; and

FIG. 6 is an enlarged plan view indicating the tensioning bolt member held in position by the surrounding sleeve or collar member.

Referring to the drawings in particular, the invention embodied therein includes a scissors generally designated 10 having co-operable lower and upper blades or blade elements 1 and 2, which are pivotal about an elongated body portion 12 of a tensioning bolt member generally designated 14.

45 In accordance with the invention, a sleeve or collar member generally designated 6 is either formed integrally with or secured to the lower blade element 1 in vertical alignment with a pivot bore or opening 16 defined therein. The bore or opening 18 of the collar member 6 is substantially the same size as the bore or opening 16 of the lower scissors element 1 and receives the body portion 12 of the tensioning bolt member 14.

The upper portion of the collar member 6 includes lateral shoulders or walls 6a and 6b which are substantially parallel to the longitudinal axis of the blade 1 and act to confine a lever arm portion 3 of the tensioning bolt member 14 in a position parallel to the axis of the blade 1. The outer end of the lever arm portion 3 is either bent downwardly or includes a protuberance 4 which bears against the outer face of the upper blade element 2. An adjusting nut 5 is threaded onto the opposite end of the tensioning bolt member 14.

When the tensioning bolt member 14 is drawn into the sleeve by the threading of the adjusting nut 5 onto the body portion 12, the protuberance 4, dependent on the amount of tensioning as set by the nut 5, is drawn against the surface of the blade 2, the lever arm 3 flexing by a small amount to permit such tensioning.

With the invention, it has been determined that the cutting action of the scissors blades 1 and 2 can be adjusted easily, rapidly and in simple manner. Once the tensioning value has been set by adjusting the nut 5, there

is no tendency for this adjusted condition to deviate, since the nut 5 is not influenced by the scissors blade movement when the scissors is opened and closed. This is true because the positions of the lower scissors blade 1, the sleeve 6, the angular lever arm 3 and the knurled nut 5 are not changed relatively during cutting when the scissors blades are pivoted about the tensioning bolt member 14 in the usual manner. However, the upper scissors blade 2 is rotated relatively to the sleeve 6 below the protuberance 4 of the lever portion 3.

While a specific embodiment of the invention has been shown and described in detail to illustrate the application of the inventive principles, it will be understood that the invention may be embodied otherwise without departing from such principles.

What is claimed is:

1. A scissors having an adjustable cutting action, comprising a pair of cooperable scissors blade elements each having aligned openings therein at their pivotal location, a tensioning bolt member including a body portion extending outwardly from said body portion and having an end bearing against the adjacent blade element and adjusting nut means threaded onto said tensioning bolt member body portion to vary the force upon which the outer end of the lever arm portion bears against the adjacent blade element.

2. A scissors according to claim 1, wherein said lever arm portion includes a portion extending substantially parallel to the face of said blades and a portion extending downwardly therefrom at the end thereof into contact with the face of the adjacent blade element.

3. A scissors according to claim 1, including means associated with one of said blade elements for orienting said lever arm portion against rotation in respect to said associated blade element.

4. A scissors blade construction, comprising a first blade element having a bore defined therethrough, a collar member connected to said first blade element and

having a bore in alignment with the bore of said first blade element, a second blade element having a bore, said collar member fitting into said bore and projecting outwardly beyond the opposite face thereof, a tensioning bolt member including a portion extending through the bore of said collar member and said first blade element and a lever arm portion extending outwardly and downwardly against a face of said second blade element, an adjusting nut means threaded onto said tensioning bolt member on the opposite end from said arm portion and against the face of said first blade element whereby to tension said lever arm portion to vary the tension between said first and second blade elements.

5. A scissors according to claim 4, wherein said tensioning bolt member lever arm portion extends substantially parallel to the face of said second blade element and includes a protuberance at the end thereof extending downwardly into contact with the face of said second blade element.

6. A scissors according to claim 4, wherein said collar includes a wall portion confining said lever arm portion in a preselected oriented position.

7. A scissors according to claim 6, wherein said lever portion is confined against movement in a position substantially parallel to the axis of said first blade element.

8. A scissors according to claim 4, wherein said collar member includes upstanding wall portions on each side of said lever portion, preventing rotative movement of said lever arm portion during the operation of said scissors.
